(57) **CLAIM**

The ornamental design for a fuel filter, as shown and described.

DESCRIPTION

FIG. 1 is a perspective view of a filter showing our new design;

FIG. 2 is a front view of the filter of FIG. 1;

FIG. 3 is a rear view of the filter of FIG. 1;

FIG. 4 is a left side view of the filter of FIG. 1;

FIG. 5 is a right side view of the filter of FIG. 1;

FIG. 6 is a top view of the filter of FIG. 1; and,

FIG. 7 is a bottom view of the filter of FIG. 1.

The broken lines depicted in the foregoing figures are for purposes of illustration only, and form no part of the claimed design.

1 Claim, 7 Drawing Sheets

FIG. 1
